UNITED STATES PATENT OFFICE

2,128,629

TOY BALLOON

Ilija Worobjoff, Steglitz, Berlin, Germany, assignor of one-half to Karl Franke, Berlin, Germany

Original application December 5, 1936, Serial No. 114,488. Divided and this application December 30, 1937, Serial No. 182,586. In Germany December 19, 1935

5 Claims. (Cl. 46—87)

This invention relates to toy balloons wherein air is forced into the balloon and the fabric thereof is placed under tension and then the balloon, when released, will rise due to discharge of air through a discharge opening, this present application being a division of my application for patent, Ser. No. 114,488, filed December 5, 1936, on Toy balloons.

In toy balloons of this character, it is necessary that the aperture of the discharge nozzle be made comparatively large, as otherwise the lift will be too small. A comparatively large nozzle aperture, however, has the disadvantage that the air within the balloon escapes too quickly so that the balloon falls to the ground in a very short time.

I have found that the lift is considerably assisted if the nozzle is made in a cup-like form, that is, is furnished with a bottom wall in which the outlet aperture is provided and if the edge of said outlet aperture is pressed inwardly so as to form a flange defining the aperture. I have also found that a hissing or whistling noise may be produced during the time when the balloon is in the air by providing a second wall disposed in spaced relation to the first named wall, this second wall being also furnished with an outlet aperture.

Three embodiments of my invention are shown in the accompanying drawing by way of example.

30 In this drawing:

Fig. 1 is an elevation of an inflated balloon provided with a nozzle constructed in accordance with this invention, the figures showing in dot-and-dash lines the balloon when deflated.

35 Fig. 2 is a bottom plan view of the nozzle.

Figs. 3, 4 and 5 are vertical sections through different embodiments of the nozzle.

In the embodiment shown in Figs. 2 and 3, the balloon 10 is shown as provided with a neck 11 and the nozzle 12, which nozzle tapers downward slightly and is provided at its upper end with a bead 13 over which the neck 11 is forced. The nozzle is provided at its lower end with a bottom wall 14 having a central aperture 15, this aperture being defined by an inwardly extending annular flange 16. By the provision of this flange 16 surrounding the outlet aperture 15, the lifting effect imparted to the balloon by the escaping air is considerably enhanced or, in other words, the balloon will stay up longer before its complete deflation than otherwise would. This flange 16 results in the contraction of the escaping air stream in excess of the contraction produced by a plain unflanged nozzle opening. The lift, of course, is produced by the impact of the stream

of air escaping through the nozzle against the exterior air.

If it be desired to produce a whistling or hissing noise when the air is expelled through the nozzle 12, there is provided, as shown in Fig. 4, a second bottom wall 17 which is disposed within the nozzle and disposed in spaced relation to the bottom wall 14. The bottom wall 17 is formed with a slightly smaller outlet aperture 18 than the aperture 15 and the wall 17 is disposed in predetermined spaced relation to the bottom wall 14.

In Fig. 5, I show another embodiment of my invention which operates in the same manner as that shown in Fig. 4 to restrict the discharge of air from the balloon and at the same time secure a whistling noise. In the form shown in Fig. 5, the nozzle 12 has a central aperture 15, but this is not formed with the inwardly extending flange 16. Fitted over the lower end of the nozzle is a cap 19 which is, however, provided with a central opening 20 and a flange 21 defining this opening. This cap has its bottom wall disposed in spaced relation to the wall 14 of the nozzle. This structure operates in precisely the same manner as the structure shown in Fig. 4, but has this advantage that the cap 19 may be readily removed if or when desired.

It is to be understood that while I have shown a balloon in which the nozzle provides for either inflation or deflation, yet the balloon might be provided with separate means for inflating the balloon which may be afterwards closed and then the air permitted to discharge through the deflating nozzle.

It is to be understood that no limitation is made to the specific forms of embodiment shown and that modifications of the embodiments illustrated are quite possible within the terms of the annexed claims without departing from the spirit of the invention.

40 What is claimed is:—

1. An inflatable toy balloon having an outlet nozzle provided with a central aperture, the nozzle being formed with an inwardly extending flange defining the aperture.

2. An inflatable toy balloon having an outlet nozzle formed with a transversely extending lower end wall apertured for the discharge of air and having an inwardly extending flange defining the aperture, the nozzle having a second wall disposed in spaced relation to the first named wall and having a central aperture.

3. An inflatable toy balloon having an outlet nozzle, the nozzle being provided with an outer end wall having a central aperture defined by an

inwardly extending flange, and an inner end wall fitting the interior surface of the nozzle and formed with a central unflanged aperture, the inner wall being in spaced relation to the outer end wall.

4. An inflatable toy balloon having an outlet nozzle formed with an end wall, the wall having a central aperture and a cap disposed over the outer end of the nozzle and having an end wall in

spaced relation to the end wall of the nozzle and having a central aperture defined by an inwardly extending flange.

5. An inflatable toy balloon having an outlet nozzle formed with a discharge aperture, the nozzle having means constructed and arranged to retard the discharge of air through the aperture. 5
